HOSIERY DISPLAY AND MERCHANDISING UNIT

Sanford Brass, Scarsdale, N. Y., assignor to Chester H. Roth Co., Inc., New York, N. Y., a corporation of New York

Application November 30, 1956, Serial No. 44,007

Term of patent 7 years

(Cl. D80—9)

FIG. 3.

FIG. 1.

FIG. 2.

Fig. 1 is a front perspective view of the hosiery display and merchandising unit showing my new design;

Fig. 2 is a side elevational view thereof; and

Fig. 3 is a rear elevational view.

I claim:

The ornamental design for a hosiery display and merchandising unit, substantially as shown.
